UNITED STATES PATENT OFFICE

2,417,225

SCREW DRIVER

Maxwell A. West and George E. West, Portland,
Oreg., assignors to Challenger Corporation,
Portland, Oreg., a corporation of Oregon

Application February 29, 1944, Serial No. 524,422

2 Claims. (Cl. 145—50)

1

This invention relates to screw drivers, both manually operated and power driven, and to drivers designed for various types of recessed-head screws as well as for the common single-slotted screw.

This invention relates especially to screws having recesses of the type described in U. S. Letters Patent No. 2,216,382, issued October 31, 1940, and U. S. Letters Patent No. 2,289,561, issued July 14, 1942 and U. S. Letters Patent No. 2,296,887, issued September 29, 1942, in which walls of the recesses are substantially vertical and parallel for a considerable distance above the bottom of the recess.

It is most desirable, in order to be able to drive such screws efficiently under all conditions, to have a driver in which the bit and shank are not rigidly connected, so that if the driver shank is moved slightly out of axial alinement with the screw the driver bit can nevertheless remain in axial alinement with the screw and thus permit the screw to be driven properly without any danger of reaming or marring the recess. A screw driver of this type is described in our U. S. Letters Patent No. 2,218,631, issued October 22, 1940, to which reference is to be made. The present invention involves certain improvements over the screw driver described in this patent.

The object of the present invention is to provide an improved driver having a bit mounted for limited universal movement in the driver shank, which driver will be simple in construction and strong enough to withstand heavy usage, particularly when power driven.

This object we attain by constructing our driver in the manner hereinafter briefly described with reference to the accompanying drawings in which:

Fig. 1 is a longitudinal elevation of a hand-operated screw driver constructed in accordance with our invention, the bit of the driver being shown in place in a screw recess;

Fig. 2 is an enlarged fragmentary section taken longitudinally through the end of the screw driver shank, showing the driver bit in place in the screw recess, but illustrating the driver shank as moved out of alinement with the axis of the screw;

Fig. 3 is a perspective view of the end of the shank of the screw driver with the driver bit removed;

Fig. 4 is a corresponding perspective view of the driver bit removed from the shank;

Fig. 5 is an end elevation or bottom plan view of the bit and shank;

Fig. 6 is a fragmentary section taken longi-

tudinally through the end of the shank similarly to Fig. 2 but with the bit entirely removed; and

Fig. 7 is a perspective view of a bit adapted for use with common single-slotted screws.

5 In Fig. 1 the shank 10 of the screw driver is shown attached to an ordinary handle 11 in the manner of any hand screw driver. It will be understood of course that the top of the shank 10 may instead be formed so as to be held in the 10 chuck of any suitable power driven means.

The bottom or bit end portion 12 of the shank is enlarged in diameter in order to accommodate the bit properly and in order to give adequate strength to the bit end of the shank, the 15 remainder of the shank 10, however, preferably being of smaller diameter as shown in Fig. 1 since a smaller diameter affords sufficient strength for the main portion and avoids excess weight and waste of material in the driver shank.

20 The enlarged end 12 of the shank has a cylindrical cavity 13 (see Figs. 3 and 6), extending upwardly a substantial distance into the shank and concentric with the axis of the shank. This cavity, however, does not extend beyond the 25 enlarged diameter portion of the shank otherwise the shank would be weakened at that point.

A plurality of longitudinal slots 14, symmetrically spaced in the wall of the cylindrical cavity 13 extend parallel to the shank axis for a short 30 distance inwardly from the end of the shank as shown clearly in Figs. 2 and 6. In the drawings we show 4 such slots spaced at intervals of 90° from each other. For all practical purposes this would be the preferred number of slots and corresponds to the number of wings on the preferred 35 form in which we make the bit, as hereinafter explained. However our invention could be carried out with a minimum of 3 slots and a greater number of symmetrical slots than the 4 illustrated could also be used. We shall confine ourselves 40 in this description to the preferred construction involving 4 slots as shown in the drawings.

The bit 15, shown clearly in Figs. 2 and 4, is quite similar to the bit described in our previous 45 Patent No. 2,218,631, above referred to, and may conveniently be made from a bar of metal of approximately cruciform cross section in the manner explained in our previous patent. This bit has 4 wings 16 of uniform thickness throughout, and in the case of screws having double slotted or cruciform recesses in the head the wings are identical in size and shape as shown. The bottom ends of the wings are made to conform to the bottom of the screw recess, as illustrated in 50 Fig. 2. At the upper or opposite end of the bit

the wings are cut away as indicated at 17 in Fig. 4, and shoulders 18 between the larger wing sections and cut away portions 17 are preferably curved slightly downwardly as shown in Fig. 2. The width of the slots 14 is made greater than the thickness of the wings 16 and the slots 14 are made deep enough radially so that their outer walls will be located beyond the outer edges of the bit wings 16. Furthermore the wings are cut away sufficiently at the portion 17 so as to be separated from the cylindrical wall of the cavity 13 of the shank when the bit and shank are in axial alignment. Finally the length of the cut away portions 17 of the bit is less than the distance between the inner ends of the slots 14 and the inner end wall of the cavity 13, as shown in Fig. 2, so that the extreme inner end of the bit does not contact the inner end wall of the cavity 13. As a consequence, when the bit is in place in the end of the shank it may be rocked to a limited extent in any direction and thus is capable of limited universal movement in the same manner as the bit described in our Patent No. 2,218,631. The rounded shoulders 18, engaging the ends of the slot 14, facilitate this freedom of movement of the bit.

In order to hold the bit in the shank a removable dowel or pin 19 is fitted in a pair of diametrically opposite holes extending through the shank beyond the ends of the slots 14. A larger diameter hole 20 is provided in the bit through which this dowel or pin 19 extends. The hole 20 is made of sufficient size to permit the shoulders 18 to bear against the bottoms of the slots 14 when the shank is pressed down on the bit when driving a screw, and also large enough to permit the desired freedom of movement of the bit. Thus any strain or wear on the dowel or pin 19 is avoided.

It will now be apparent that the bit functions in substantially the same manner as the bit described in our Patent No. 2,218,631. However in the improved construction which we have provided in the present invention the slots in the shank for accommodating the bit wings do not extend entirely across the shank. We have found that this is a considerable advantage and a desirable improvement over our previous driver in view of the greater strength afforded to the driver in comparison with the amount of material used in the shank, reducing the tendency of breakage and also considerably improving the driver in appearance. When the slots in the shank extend transversely entirely across the end of the shank, in the manner described in our previous patent, there is a danger that the quarter section of the slotted shank, located between the slots, might be broken off under heavy usage or rough treatment, especially in power driven drivers. However breakage of this end of the shank in our improved driver under similar conditions is practically impossible due to the added strength afforded by the outer wall of the shank which completely encompasses the slots.

Another advantage in our improved driver over the driver of Patent No. 2,218,631 is that the engagement of the shoulders 18 of the bit with the ends of the slots, when the bit, shank and screw are all in axial alignment, exerts a greater tendency to maintain such alignment than would occur if the corresponding engagement between bit and shank were confined to the rounded inner ends of the wings, in the manner provided in our previous patent, and in our present construction no additional means, such as the spring shown in

one form of the driver of the previous patent, is required to cause the bit and shank to assume normal axially aligned position when conditions permit this in the driving of a screw.

As previously indicated, the driving end of the bit which projects from the driver shank, may be made in any desirable form to coincide with a particular type of screw and screw recess. In Fig. 7, for example, we show how the bit if formed with four wings in the manner previously described, may be similarly modified and adapted for ordinary single-slotted screws. In the bit of Fig. 7 one pair of the wings 21 are tapered to the wedge point 22, similar to the wedge point in a conventional screw driver for single-slotted screw. The other pair of wings 23 are cut away and thus their bottom ends merge into the wedge point 22 as shown.

Various modifications in the tip of the bit would of course be possible within the scope of our invention. The fact that the bit can be removed from the shank merely by the withdrawing of the dowel or pin 19 not only enables worn or damaged bits to be easily replaced, but also enables bits with differently shaped tips to be used with the same shank if desired, thus resulting in an economical type of driver adaptable for screws with specially formed recesses as well as the common single-slotted screws.

We claim:

1. In a screw driver a shank, a cylindrical cavity in the end of said shank concentric with the shank axis, a plurality of identical symmetrically-spaced longitudinally-extending slots in the wall of said cavity, said slots extending inwardly from the end of the shank and parallel to the shank axis, the length of said slots being less than the length of said cavity, the radial depth of said slots being substantially less than the thickness of the shank wall about said cavity, a movable bit in said cavity, said bit having wings corresponding to said slots, the thickness of said wings being less than the width of said slots, the radial extent of said wings from the bit axis being less than the radial distance of the bottoms of said slots from the shank axis, each of said wings having an identical cut away portion at the inner end of the bit, a shoulder on each wing between said cut away portion and the main wing section, said shoulders adapted to engage the inner ends of said slots respectively, said cut away portions being reduced sufficiently to allow clearance between the reduced wing portions and the cavity wall, the length of said reduced wing portions being less than the distance between the inner ends of said slots and the inner ends of said cavity, and a pin extending diametrically through said shank and cavity, said pin extending through a hole in said bit, said hole being of larger diameter than said pin, whereby said bit can be given limited universal movement out of axial alignment with said shank when necessary, and pressure on said bit by said shank causing said slot ends to engage said shoulders will tend to bring said bit into axial alignment with said shank.

2. A screw driver comprising a shank, a cylindrical cavity in the end of said shank concentric with the shank axis, four identical symmetrically-spaced longitudinally-extending slots in the wall of said cavity, said slots extending inwardly from the end of the shank and parallel to the shank axis, the length of said slots being less than the length of said cavity, the radial depth of said slots being substantially less than the

thickness of the shank wall about said cavity, said shank being of increased diameter about said cavity to provide for adequate thickness of said wall, a movable bit in said cavity, said bit having four wings corresponding to said slots, the thickness of said wings being less than the width of said slots, the radial extent of said wings from the bit axis being less than the radial distance of the bottoms of said slots from the shank axis, each of said wings having an identical cut away portion at the inner end of the bit, a rounded shoulder on each wing between said cut away portion and the main wing section, said shoulders adapted to engage the inner ends of said slots respectively, said cut away portions being reduced sufficiently to allow clearance between the reduced wing portions and the cavity wall, the length of said reduced wing portions being less than the distance between the inner ends of said slots and the inner end of said cavity, and a pin extending diametrically through said shank and cavity between the inner ends of said slots and the inner end of said cavity, said pin extending through a hole in the reduced portion of said bit, said hole being of larger diameter than 25

10

5 said pin, whereby said bit can be given limited universal movement out of axial alignment with said shank when necessary, and pressure on said bit by said shank causing said slot ends to engage said shoulders will tend to bring said bit into axial alignment with said shank.
